UNITED STATES PATENT OFFICE.

JAMES L. NORTON, OF BUFFALO MILLS, PENNSYLVANIA.

GRAIN-DRIER.

SPECIFICATION forming part of Letters Patent No. 224,217, dated February 3, 1880.

Application filed December 8, 1879.

To all whom it may concern:

Be it known that I, JAMES L. NORTON, of Buffalo Mills, in the county of Bedford and State of Pennsylvania, have invented certain new and useful Improvements in Grain-Driers; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan or top view. Fig. 2 is a longitudinal axial section. Fig. 3 is an end view. Fig. 4 is a vertical cross-section on line $x-x$ in Fig. 1, showing the slide and lever for regulating the feed of grain to the drier; and Fig. 5 is a similar section taken on line $y-y$, Fig. 2.

Similar letters of reference indicate corresponding parts in all the figures.

This invention has relation to grain-driers; and it consists in the improvement hereinafter described, and particularly pointed out in the claims.

In the drawings, A is a cylindrical case, which surrounds a smaller cylinder, B, open at one end, and provided with a central shaft, C, carrying an Archimedean screw, D, the blades or spiral of which impinge upon the walls of the inner cylinder, B.

The outer cylinder, A, has a flange, a, at one end, so as to form a cylindrical closed steam-chamber, b, surrounding the inner open cylinder, B.

Steam is admitted to the chamber b through a pipe, E, on top, and escapes through the pipe F, under the bottom of the cylinder, both of which pipes may be provided with suitable valves or stop-cocks.

G is a safety-valve placed upon the top of cylinder A, and H is a short tube reaching through the steam-chamber b from the outside, and provided with a recessed plug, I, the recess i of which has an aperture, h, which, by turning the plug in its tube H, may be set so as to register with an opening, k, in the tube, which opens into the steam-chamber b. It follows that by turning plug I so as to bring

the apertures h k opposite to each other, steam will pass from the steam-chamber b, through the apertures h k and recess i, into the open grain-cylinder B, by which the grain contained in said cylinder may be moistened, if too dry.

Grain is fed to cylinder B through a hopper, K, which terminates in a tube, K', impinging upon the shaft C of the Archimedean screw D.

The hopper K with its tube may be adjusted vertically by means of a slide, L, provided with a bail or keeper, l, through which tube K' is inserted, the said slide being operated by an angle-lever, M M'. By depressing the handle M' of this lever the hopper with its tube is raised, increasing the distance between the lower end of the tube and shaft C, and thus enabling a larger quantity of grain to be fed into cylinder B in a given time. Hence the feed of grain to the drier may always be regulated by simply adjusting the lever M M', without stopping or otherwise interfering with the operation of the machine.

The central shaft, C, with its Archimedean screw or propeller D, is rotated by means of a pulley, d, at one end, so as to pass the grain slowly and evenly through the drying-cylinder until it escapes from the open end of this into the hopper N, through which it is fed to the burrs.

I prefer, for the sake of convenience and to economize space, to suspend this apparatus by hangers under the joists of the roof or ceiling of the mill, where it is entirely out of the way, and yet in a convenient position for feeding the grain to the burrs.

Having thus described my invention, I claim and desire to secure by Letters Patent of the United States—

1. In a grain-drier, the combination, with the drying-cylinder B, provided with the rotating shaft C and Archimedean screw or propeller D, of the vertically-adjustable hopper K K', slide L, having keeper l, and lever M, provided with the handle M', substantially as and for the purpose herein shown and described.

2. The herein-described apparatus for drying grain, consisting of the double cylinder A

B, forming a cylindrical hollow steam-chamber, *b*, which is provided with an inlet, *E*, outlet *F*, safety-valve *G*, and tube *H*, having aperture *k*, plug *I*, provided with the recess *i* and aperture *h*, vertically-adjustable hopper *K* *K'*, rotating shaft *C*, provided with an Archimedean screw or propeller, *D*, and operating-pulley *d*, and receiving-hopper *N*, all constructed and combined to operate substan-

tially as and for the purpose herein shown and so specified.

In testimony that I claim the foregoing as my own I have hereunto affixed my signature in presence of two witnesses.

JAMES L. NORTON.
